(57) **CLAIM**

The ornamental design for a jewelry ring, as shown and described.

DESCRIPTION

FIG. 1 is a front top right-side perspective view of a jewelry ring, showing our new design;

FIG. 2 is a front bottom right-side perspective view thereof;

FIG. 3 is a front elevation view thereof, the rear elevation view being an identical image thereof;

FIG. 4 is a left-side elevation view thereof, the right-side elevation view being an identical image thereof;

FIG. 5 is a top plan view thereof; and,

FIG. 6 is a bottom plan view thereof.

The use of stippling indicates a contrasting appearance relative to the adjacent line-shaded portion of the jewelry ring.
